SHOE SOLE

Theodore Papoutsy, 59 Wingate St., Haverhill, Mass.

Filed May 31, 1963, Ser. No. 75,146

Term of patent 14 years

(Cl. D7—5)

FIG. 1 is a bottom plan view of a shoe sole showing my new design.

FIG. 2 is a side elevational view thereof; the broken line showing of a shoe being for purposes of illustration only.

FIG. 3 is a section taken on the line 3—3 of FIG. 1.
FIG. 4 is a section taken on the line 4—4 of FIG. 1.

I claim:

The ornamental design for a shoe sole, substantially as shown and described.
